United States Patent Office.

JOHN T. WEBSTER, OF NEW YORK CITY, ASSIGNOR TO DEBORAH POWERS, ALBERT E. POWERS, AND NATHANIEL B. POWERS, OF LANSINGBURGH, NEW YORK.

Design No. 2,705, dated July 16, 1867.

DESIGN FOR FLOOR OIL-CLOTH.

The Schedule referred to in these Letters Patent and making part of the same.

TO ALL WHOM IT MAY CONCERN:

Be it known that I, JOHN T. WEBSTER, of the city, county, and State of New York, have invented or produced a new Design for Floor Oil-Cloths, or other fabrics, which I verily believe has not before been known or produced, and that the particulars of said design are fully shown and set forth by the drawings accompanying this specification, which are hereby declared to be a part of the same; and what is desired to be secured by Letters Patent of the United States is—

The design shown upon said drawings, which I do hereby claim to be my invention.

JOHN T. WEBSTER.
